UNITED STATES PATENT OFFICE.

HERMAN F. BALL, OF BRONXVILLE, NEW YORK, AND HAL R. STAFFORD, OF PLAINFIELD, NEW JERSEY.

LOCOMOTIVE-ENGINE.

1,208,078.

Specification of Letters Patent. Patented Dec. 12, 1916.

Application filed August 29, 1916. Serial No. 117,897.

To all whom it may concern:

Be it known that we, HERMAN F. BALL, of Bronxville, in the county of Westchester and State of New York, and HAL R. STAFFORD, of Plainfield, in the county of Union and State of New Jersey, have jointly invented a certain new and useful Improvement in Locomotive-Engines, of which improvement the following is a specification.

10 Our invention relates to locomotive engines for heavy freight or pushing service, of the class in which two groups or sets of coupled driving wheels are rotated by separate and independent pairs of steam cylinders, and its object is to provide a locomotive of such class, in which the maximum hauling capacity derivable from the operation of two pairs of cylinders may be exerted, with the restriction, to the minimum 20 length, of the rigid wheel base, and the maintenance of invariable lateral relation of the boiler to the frame and cylinders, with the consequent elimination of joints in steam conveying pipes.

25 The improvement claimed is hereinafter fully set forth.

In the accompanying drawings: Figure 1 is a diagrammatic side view, in elevation, of a locomotive engine illustrating an embodiment of our invention; Fig. 2, a vertical transverse section, the right hand half taken on the line *a a* of Fig. 1, and the left hand half, slightly in advance of said line; Fig. 3, a similar section, the right hand half 35 taken on the line *b b* of Fig. 1, and the left hand half, slightly in rear of said line; Fig. 4, a view similar to Fig. 1, except in showing a different disposition of cylinders; and, Fig. 5, a diagrammatic side view of the 40 wheels and cylinders, illustrating a structural modification in the manner of coupling the driving wheels.

In the practice of our invention, referring descriptively to the specific embodiment thereof which is exemplified in Figs. 1, 2 and 3, we provide a rigid frame, 1, comprising two side frame members of the ordinary construction, connected by suitable cross ties in the usual manner. The boiler, 2, is secured at its front end to, and supported on, a pair of front cylinder saddles, 3^a, each of which is cast integral with one of a pair of front steam cylinders, 3, and is firmly secured to the adjacent side. The member of the locomotive frame, 1. The rear end of the boiler is supported on the frame in any suitable and convenient manner, and is preferably connected by the usual expansion plates or shoes, so as to provide for longitudinal expansion and contraction of the boiler, under variations of temperature, without permitting lateral movement, relatively to the frame. A pair of rear steam cylinders, 4, is secured to the frame, adjacent to the rear end of the boiler, 60 preferably through half connecting members, 4^a, cast integral with the cylinders and secured one to the other centrally, and to the side members of the frame.

A plurality of pairs of driving wheels, 5, 70 secured upon axles, 5^a, 5^b, 5^c, is interposed between the front and rear cylinders, the axles of all of said pairs of wheels, except the front and rear pairs, being journaled in driving boxes mounted in pedestals on the 75 side frame members, in the ordinary manner. Without being limited to any specific number of driving axles and wheels, the number thereof is determined by the maximum rigid wheel base which is permissible 80 under the conditions of operation for which the locomotive is designed, and the driving axles are disposed as closely together as the diameter of the wheel flanges will permit. The front driving axle, 5^b, and the rear 85 driving axle, 5^c, are mounted in lateral motion driving boxes, 6, which afford said axles a determined degree of lateral movement, relatively to the frame members, to facilitate the traverse of the locomotive to, 90 through, and from curved portions of the track, and the determined rigid wheel base of the locomotive is thereby reduced to the minimum, and constituted by the longitudinal distance between the axis of the driving axle next succeeding the front one, 5^b, 95 and that next preceding the rear one, 5^c. The lateral motion appliances of said front and rear driving axles, do not, in and of themselves, form part of our present invention, and they are not therefore in detail herein set forth. In the instance exemplified, they are of the construction set forth in Letters Patent of the United States No. 1,181,194, granted and issued to William 100 E. Woodard and Samuel S. Riegel, under date of May 2, 1916, but any other means of providing the capacity of lateral motion in

the operation of the front and rear driving axles may be applied, as deemed most desirable by the constructor.

The forward pair of driving wheels, and 6 one or more pairs next succeeding them, constitute what may be termed descriptively, the "forward group" of driving wheels, and the rear pair of driving wheels, together with one or more pairs next preceding them, 10 constitute the "rear group". The wheels of the forward group are rotated by the pistons of the front steam cylinders, 3, through their piston rods, 3^b, cross heads, 3^c, main connecting rods, 7, and coupling or side rods, 8. The wheels of the rear group are rotated by the pistons of the rear steam cylinders, 4, through their piston rods, 4^b, cross heads, 4^c, main connecting rods, 7^a, and coupling or side rods, 8^a. As shown 15 in Figs. 1 and 4, the axles of the rear pair of driving wheels of the forward group and the front pair of the rear group, are not coupled one to the other, but said axles may, if preferred, be coupled by side rods, 8^b, as 20 shown in Fig. 5.

A locomotive of the construction above described is particularly adapted to the application of compound cylinders, and such application, which, while preferred, is not 25 an essential of the leading characteristic features of our invention, is illustrated in the drawings.

As shown in Figs. 1, 2, 3 and 5, the high pressure cylinders are located at the rear of 30 the locomotive and receive their supply of steam from the ordinary main steam pipe or dry pipe, through side steam pipes, 9, extending along the outside of the boiler, from connections with the main steam 35 pipe, to the valve chests, 4^a, of the rear cylinders. Steam is exhausted from said cylinders and valve chests, through a rigid receiver pipe, 10, extending forwardly, below the boiler, to the valve chests, 3^a, of the front cylinders, from which it is, after operating on the pistons thereof, exhausted to the stack in the usual manner.

In the construction shown in Fig. 4, the 40 front cylinders, 3, are of smaller diameter than the rear cylinders, 4, and act as high pressure cylinders, steam being admitted to their valve chests, 3^a, directly from the main steam supply pipe, through outside steam pipes, 11, and being exhausted into the rear 45 low pressure cylinders, 4, through a receiver pipe, 10^a, extending below the boiler to the valve chests, 4^a, of the low pressure cylinders. Steam is exhausted from the low 50 pressure cylinders through final exhaust pipes, 12, extending along the sides of the boiler, to a connection with an ordinary discharge exhaust pipe in the smoke box.

Among the substantial advantages of the 55 invention which will be apparent to those familiar with the construction and opera-

tion of locomotives, there may be specially noted the exertion of the maximum hauling capacity obtainable from two pairs of steam cylinders with a restriction to the minimum length of rigid wheel base that can be advantageously adopted, and the elimination of articulated frames, and flexible receiver and exhaust pipes, the cost of construction and maintenance of which, in locomotives of the well known "Mallet" type, constitutes 75 a very large item of structural charge. The objectionable operative feature of the latter type which is presented in the lateral movements and angularity of the boiler, relatively to the frame in passing curves, is also 80 eliminated, and the advantageous one of attaining continuity in draw bar pull, by the application of high pressure and low pressure cylinders to separate groups of driving wheels, and the consequent capacity of 85 compensation for loss of work by slipping of the wheels of either group, is as fully attainable as in the Mallet type.

We claim as our invention and desire to 90 secure by Letters Patent:

1. In a locomotive engine, the combination of a frame; a boiler supported thereon and connected thereto without capacity of relative lateral movement; a plurality of driving axles mounted therein, each carrying 95 a pair of driving wheels; lateral motion driving boxes in which the front and rear driving axles are journaled; a pair of front steam cylinders having their pistons coupled to a driving axle in rear of the front 100 one; and a pair of rear steam cylinders having their pistons coupled to a driving axle in front of the rear one.

2. In a locomotive engine, the combination of a frame; a boiler supported thereon 105 and connected thereto without capacity of relative lateral movement; a plurality of driving axles mounted therein, each carrying a pair of driving wheels; coupling rods connecting said axles into a forward and a 110 rear group; lateral motion driving boxes in which the front and rear driving axles are journaled; a pair of steam cylinders having their pistons coupled to an axle of the forward group; and a pair of steam cylinders 115 having their pistons coupled to an axle of the rear group.

3. In a locomotive engine, the combination of a frame; a boiler supported thereon and connected thereto without capacity of 120 relative lateral movement; a plurality of driving axles mounted therein, each carrying a pair of driving wheels; lateral motion driving boxes in which the front and rear driving axles are journaled; a pair of high 125 pressure steam cylinders having their pistons coupled to a driving axle which is not journaled in lateral motion driving boxes; and a pair of low pressure cylinders having 130 their pistons coupled to another driving axle

which is not journaled in lateral motion driving boxes.

4. In a locomotive engine, the combination of a frame; a boiler supported thereon and connected thereto without capacity of relative lateral movement; a forward and a rear group of coupled driving axles, each axle being mounted in the frame and carrying a pair of driving wheels; lateral motion driving boxes in which the front axle of the forward group and the rear axle of the rear group are journaled; a pair of steam cylinders having their pistons coupled to an axle of the forward group; and a pair of steam cylinders having their pistons coupled to an axle of the rear group.

5. In a locomotive engine, the combination of a frame; a boiler supported thereon and connected thereto without capacity of relative lateral movement; a forward and a rear group of coupled driving axles, each axle being mounted in the frame and carrying a pair of driving wheels; lateral motion driving boxes in which the front axle of the forward group and the rear axle of the rear group are journaled; a pair of steam cylinders secured to the frame, in front of the forward group, and having their pistons

coupled to an axle of said group; and a pair of steam cylinders secured to the frame, in rear of said group, and having their pistons coupled to an axle thereof.

6. In a locomotive engine, the combination of a frame; a boiler supported thereon and connected thereto without capacity of relative lateral movement; a forward and a rear group of coupled driving axles, each axle being mounted in the frame and carrying a pair of driving wheels; lateral motion driving boxes in which the front axle of the forward group and the rear axle of the rear group are journaled; a pair of high pressure steam cylinders having their pistons coupled to an axle of one of said groups; and a pair of low pressure steam cylinders having their pistons coupled to an axle of the other group.
